(57) **CLAIM**

The ornamental design for a smartphone, as shown and described.

DESCRIPTION

FIG. 1 is a top, right, rear orthogonal view of a smartphone showing the new design;

FIG. 2 is a bottom, right, rear orthogonal view of the invention illustrated in FIG. 1;

FIG. 3 is a front view of the invention illustrated in FIG. 1;

FIG. 4 is a rear view of the invention illustrated in FIG. 1;

FIG. 5 is a right side view of the invention illustrated in FIG. 1;

FIG. 6 is a left side view of the invention illustrated in FIG. 1;

FIG. 7 is a top view of the invention illustrated in FIG. 1; and,

FIG. 8 is a bottom view of the invention illustrated in FIG. 1.

The broken lines in the drawings depict portions of the smartphone that form no part of the claimed design. The parallel diagonal shading lines indicate transparency.

1 Claim, 6 Drawing Sheets
